UNITED STATES PATENT OFFICE.

WILLIAM H. SANBORN, OF LARCHMONT, NEW YORK, ASSIGNOR OF ONE-HALF TO
HERBERT L. GRAY, OF WASHINGTON, DISTRICT OF COLUMBIA.

FEED-BAG FOR HORSES.

1,252,037.

Specification of Letters Patent.

Patented Jan. 1, 1918.

Application filed June 13, 1917. Serial No. 174,606.

To all whom it may concern:

Be it known that I, WILLIAM H. SANBORN, a citizen of the United States, and a resident of Larchmont, in the county of 5 Westchester and State of New York, have invented an Improvement in Feed-Bags for Horses, of which the following is a specification.

My present invention relates particularly 10 to feed bags for horses, my primary object being the provision of a novel, simple and practical construction by which to meet the constantly increasing demands of humane societies and the public that greater comfort 15 be provided for domestic animals, especially the horse, and which have not, as yet, been met in the construction of feed bags from which horses have been compelled to eat their grain while standing in the street at 20 tached to vehicles.

Generally speaking my invention proposes a feed bag which gives direct and open ventilation by constructing the front of the bag in sections, each separate section extending 25 down into the next lower section and separated from it by spacing members or blocks of leather, wood, cork, or other material, placed between the sections at intervals and secured in place by rivets, stitching 30 and the like.

In this manner of constructing the front of the feed bag, open spaces are provided for ventilation which cannot become clogged by any means or conditions. The warm 35 breath of the horse will rise through the openings, the cooler fresh air will enter from the top of the bag in a volume equal to the amount exhaled by the horse, and the circulation of air will be maintained even when the horse's nose is at the bottom of 40 the bag.

In the accompanying drawing illustrating my invention—

Figure 1 is a perspective side view illustrating the practical application of my invention.

Fig. 2 is a vertical sectional view taken through the bag removed.

Fig. 3 is a horizontal section taken substantially on the line 3—3 of Fig. 2.

Fig. 4 is an enlarged sectional view through a portion of the front of the bag.

Fig. 5 is a view similar to Fig. 4, illustrating a slightly modified form.

Referring now to these figures my invention contemplates the provision of a feed bag having a base 10, side portions 11 to which the attaching devices 12 are connected, and a rear portion 13, the side portions 11 and rear portion 13 being formed in one 60 piece and attached to the side and rear portions of the base 10.

The front portion of the bag consists of a vertical series of horizontally extending sections 14, the lower edge of the lowest 65 section of which is connected to the forward portion of the base 10. These front sections 14 extend, and are connected at their ends, to the side portions 11 of the bag and the lower portions thereof depend inwardly of, 70 and below, the upper edge of the next lowermost section in the lapping relation plainly seen by reference to Figs. 2, 4 and 5.

These lapping edges of the several sections 75 14 are connected in spaced relation by suitable spacing members securely fastened thereto as by means of rivets 15, the spacing members being disposed at intervals along the front portion of the bag so as to provide openings between them and between 80 the lapped portions of the front sections to bring about and maintain the circulation previously spoken of.

These spacing members may consist of 85 juxtaposed strips of leather or other material of like nature, as seen at 16 in Figs. 2, 3 and 4, or solid one-piece blocks of wood or cork or similar comparatively light material, as seen at 17 in Fig. 5.

It is to be observed, furthermore, that the 90 depending edge 18 of each of the sections 14 extends inwardly and downwardly beyond the spacing members and being of a flexible material, of any of the various natures usually employed in the construction 95 of feed bags, these depending edges are capable of movement outwardly against the inner surfaces of the next lowermost section so as to close the openings previously described and thus act as check valves to prevent displacement of grain or other material contents of the bag.

Thus, the bag being half filled in the first instance, the depending inner edges 18 of the lower sections will be forced outwardly 105 into closed position by the contents, leaving the lower edges 18 of those sections above in open position to provide for the neces-

sary circulation, which is increased as the contents are devoured, due to the opening of the previously closed edges.

It is obvious that my invention provides a simple, practical construction for the above purpose, capable of ready, inexpensive manufacture and of practical, efficient use in carrying out the objects first-mentioned.

I claim:

- 10 1. A feed bag having a base, side and rear portions in one piece attached to the base, a front portion consisting of a vertical series of sections extending horizontally between the side portions and connected at their ends to said side portions, the lower edge of each of said sections depending inwardly of, and downwardly below, the upper edge of the next lowermost section, members connecting the said upper and lower edges of the sections in spaced apart relation and disposed therebetween at intervals therealong, the said lower inner edges of the several sections depending freely below the said spacing members and movable 25 outwardly against the inner surfaces of the next lowermost sections to close the openings between the sections.
- 20 2. A feed bag having a vertically lapping series of transversely extending sections at its front portion, the lower edge of each of
- 25
- 30

Copies of this patent may be obtained for five cents each, by addressing the "Commissioner of Patents, Washington, D. C."

which sections depends inwardly of, and below, the upper edge of the next lowermost section, and is connected in spaced relation thereto said sections normally forming openings therebetween, and having means to close said openings under pressure of material within the bag.

3. A feed bag having a vertical series of transversely extending sections at its front portion, the lower edge of each of which sections depends inwardly of, and below, the upper edge of the next lowermost section to form an opening therebetween, and a plurality of spacing members extending between and connected to the lapping edges of said sections at intervals therealong, said sections having portions thereof arranged to close the said openings therebetween.

4. A feed bag having a vertical series of transversely extending sections at its front portion, the lower edge of each of which sections depends inwardly of, and below, the upper edge of the next lowermost section, and a plurality of spacing members extending between and connected to the lapping edges of said sections at intervals therealong, the said depending lower edges of the sections extending freely below the said spacing members, for the purpose described.

WILLIAM H. SANBORN.
